UNITED STATES PATENT OFFICE.

JOHN W. SEIFERT, OF HOUSTON, TEXAS.

WASHING-MACHINE.

1,373,917.

Specification of Letters Patent.

Patented Apr. 5, 1921.

Application filed March 27, 1920. Serial No. 369,288.

To all whom it may concern:

Be it known that I, JOHN W. SEIFERT, a citizen of the United States, residing at Houston, in the county of Harris and State 5 of Texas, have invented new and useful Improvements in Washing-Machines, of which the following is a specification.

This invention relates to washing machines, and one of its objects is to provide 10 a washing machine whereby individual pieces of goods may be washed, similar to hand-washing, but with greater speed and also with other material advantages over the ordinary hand-washing process.

Another object of the invention is to provide 15 a washing machine which gives a gentle but highly efficient rubbing action on the goods, which rubbing action may be controlled to a nicety by the operator, and which affords a greater extent of rubbing 20 surface than is possible with the use of the ordinary washboard in hand-washing.

A still further object of the invention is to provide a washing machine which is simple 25 and inexpensive in construction, compact and capable of being clamped upon the side of an ordinary wash-tub, and economical in the use of soap and water.

The invention consists of the features of 30 construction, combination and arrangement of parts, hereinafter fully described and claimed, reference being had to the accompanying drawings, in which:—

Figure 1 is a front elevation of a washing machine constructed in accordance with 35 my invention.

Fig. 2 is a vertical transverse section taken centrally through the machine.

Fig. 3 is a detail section on the line 3—3 40 of Fig. 1.

Fig. 4 is a detail view showing the hinged connection of the goods clamping rod at one side of the drum or cylinder.

Fig. 5 is a detail view showing the fastening means for the free end of the goods clamping rod at the opposite side of the 45 drum or cylinder.

Fig. 6 is a detail view showing a feature of construction.

In the practical embodiment of my invention I provide a washing machine having 50 a frame structure including a base or bottom bar 1, standards or uprights 2 rising therefrom, and an upper or pressure bar 3 extending between the upper ends of said uprights and connected thereto as herein-

after described. The standards 2 are provided with suitable bearings for a horizontal shaft 4 provided at the front end thereof with an operating crank handle 5. A 60 rubbing cylinder or drum 6 is fixed upon said shaft for movement therewith between the standards 2, said cylinder or drum comprising a pair of end disks or heads 7 fixed to the shaft and a body covering 8 of woven wire or other suitable perforate or reticulated material. The material 8 forms the cylindrical body portion of the drum, permitting of the circulation of the suds water therethrough, slots or openings 9 being provided in the end heads 7, adjacent to their peripheries, to permit the water to flow freely from end to end of the drum and outwardly at the ends thereof.

The wire cloth or body of reticulated material 8 forms the rubbing surface of the drum, and the edges of this material are tacked or otherwise suitably fastened to the heads 7. Protecting strips 10, of metallic tape or other suitable material are preferably secured over the edges of the wire cloth, so as to cover the same and form smooth surfaces at the ends of the rubbing surface to prevent liability of injury to the goods or clothes being washed. In practice, 85 the machine may be employed for cleansing single pieces of goods at a time, similar to hand-washing, and provision is made for securing the article at one of its corners or at a suitably restricted point to the surface of the drum. To this end the drum is provided at one end in its circumference with a longitudinal groove 11 to receive the portion of the article to be secured, a clamping rod 12 being provided to clamp such 90 portion of the article in position. This rod 12 is hinged at one end, as indicated at 13, to one of the end heads of the drum, and a pivoted latch 14 is provided upon the opposite head of the drum to engage the 95 free end of the rod and hold the rod seated in the groove 11 in clamping position. The groove 11 is so arranged with relation to the crank handle 5, that when said handle is at rest and in its normal depending position, as shown in Fig. 1, the groove 11 will be disposed at the forward portion of the cylinder in position for the ready and convenient clamping or release of the goods.

Provided for co-operation with the drum 110 or cylinder 6 is substantially semi-circular rubbing bed 15. This is arranged so as to

substantially surround the lower half of the cylinder 6, and comprises a semi-cylindrical curved strip of corrugated sheet metal or like flexible or resilient material, perforations 16 being provided in said bed for the passage of the suds water therethrough. This bed 15 also includes a supporting cradle consisting of rods 17 and supporting strips or bands 18. The rods 17 are arranged longitudinally of and at the front and rear of the cylinder, while the bands 18 are arranged in suitably spaced relation and are permanently connected with the rods and extend around the bed 15. As shown, the corrugated metal bed 15 has its longitudinal edges bent to form eyes 19 which embrace the rods 17, and the bands 18 are provided with similar eyes 20 which embrace the rods, the connections described affording a sufficient pivotal engagement between the parts mentioned to permit the bed and bands to flex freely so that the bed may bear against the rubbing surface of the cylinder 6 with greater or less force.

Spring hangers 21 are provided for yieldingly supporting the cradle and bed from the standards or uprights 2. Each of these hangers comprises a spring metal band having a substantially straight central portion 22 and curved or bent end portions 23. The straight central portions 22 of the spring hangers rest upon the upper ends of the standards 2 and are held in clamping engagement therewith by the upper cross bar or pressure bar 3, while the extremities of the curved ends 23 of said hangers are formed with eyes 24 which pivotally engage the ends of the rods 17, whereby the bed 15 and its supporting cradle are resiliently suspended from the standards 2 by the hanger springs.

The bar 3 is preferably of channeled form and has its flanges 25 downwardly directed and arranged to bear against the straight central portions 22 of the hanger springs 21 on opposite sides of the standards 2, and said bar 3 is adjustably secured to the upper ends of the standards by angular brackets 26, said brackets having their depending portions provided with slots 27 for the passage of fastening screws 28 or the like, whereby the bar 3 is slidably connected with the standards and may be fixed whenever desired in adjusted position. The ends of the bar 3 are perforated for the passage of screws 29 provided with adjusting nuts 30, said screws passing downwardly through openings in the central portions 22 of the hanger springs 21 and having heads 31 seated in sockets in the upper ends of the standards 2, whereby, through adjustments of the nuts 30, the flanges 25 may be caused to bear with greater or less pressure upon the portions 22 of the hanger springs on opposite sides of the standards 2. Through

the adjusting and fastening connections described it will be readily understood that by varying the pressure of the bar 3 on the hanger springs 21 the up pulling pressure on the ends 23 of said springs upon the bed 15 may be regulated, to vary the rubbing pressure of the bed 15 against the surface of the cylinder 6 accordingly. This follows from the fact that when downward pressure upon the hanger springs 21 is exerted by the flanges 25, the intermediate portions of the hanger springs will be flattened to a greater extent, thus tending to force the curved ends 23 outwardly and to decrease their arc of curvature, resulting in an upward spring pull upon the edges of the bed 15, whereby said bed is drawn with greater force toward the surface of the cylinder 6. A relaxation of the pressure of the flanges 25 on the central portions of the spring hangers 21, on the contrary, will allow such portions to assume a slight arc of curvature, thus increasing the arc of curvature of the curved ends 23 and allowing the same to elongate, thus relaxing the pressure of the bed 15 on the surface of the cylinder 6. It will be understood, therefore, that the pressure of the resilient bed against the cylinder may be regulated to a nicety, so that the most delicate articles of fabric may be washed without liability of injury, and that after the spring hangers have been adjusted to exert the desired tension they may be maintained in such position as long as desired by fixing the pressure bar 3 in adjusted position.

Supported by the base bar 1 between the same and the shaft 4 is a pan or receptacle 32 to hold the suds water or other cleansing fluid, said pan being provided at its front with a drain valve 33 whereby the suds water may be drawn off therefrom whenever desired. The pan is adapted to be removably supported upon the base bar 1 and is properly formed to allow it to be inserted and withdrawn at a suitable angle without the necessity of disturbing any of the other parts. In practice this pan is filled with suds water or other cleansing fluid up to a level sufficient to submerge the lower portions of the cylinder and bed disposed therein, so that in the operation of the machine there will be a constant flow of water between the rubbing surfaces to effect the rapid and efficient cleansing of the article being washed. The washing machine constructed in accordance with my invention is very compact and may be supported for use upon a stationary wash-tub in a manner similar to that in which an ordinary wringer is supported, the bar 1 being provided with a clamp 34 whereby it may be clamped to the upper edge of one of the walls of a stationary tub 35, as indicated in Figs. 1 and 2. When so arranged the drain valve 33 may be disposed to overhang the body of the tub, to

permit the water from the pan 32 to drain into the tub, so that soiled water may be allowed to constantly drain out of the pan and the latter replenished with clean water from time to time as may be required when the washing operation is carried on for a considerable period. Suitable fastening members 36 may be provided for holding the pan in position while in use.

In the operation of the machine, the article to be washed is clamped at one of its corners in the groove 11 of the drum or cylinder 6 by the clamping bar 12, and such article spread over the face of the drum, so that in the rotation or oscillation of said drum the article will be brought between opposed rubbing surfaces of the drum and bed for a cleansing action. As the article is rubbed between such surfaces it will be subjected to the cleansing operation of the rubbing action and the circulation of the water passing through the openings in the drum and bed, resulting in the rapid removal of the dirt and its drainage off into the pan 32. In the turning or revolving motions of the drum or cylinder the article will be periodically withdrawn from between the rubbing surfaces and at such times may be soaped and adjusted over the face of the drum by the operator so as to insure the exposure of all portions of its surface to the succeeding rubbing actions. Inasmuch as the bed bears resiliently against the face of the drum, the article to be cleansed will be held lightly pressed between the rubbing surfaces, and this pressure may be regulated as desired according to the fineness or coarseness of the fabric, so that goods of even the most delicate texture may be rapidly and thoroughly cleansed without injury. If desired, the bar 3 may form a support for a soap tray or receptacle 37, allowing a cake of soap kept in convenient position for hand-soaping of the goods spread over the face of the drum.

Having thus fully described my invention, I claim:

1. A washing machine including a base, standards rising therefrom, a rotary rubbing drum supported by the standards, a foraminous concave rubbing bed of flexible material embracing the lower portion of the drum, springs centrally mounted upon the uprights and having curved or bowed ends extending downwardly therefrom and connected at their free ends with the edges of the rubbing bed on opposite sides of the rotary rubbing drum, and means adjustably mounted upon the uprights for engaging and regulating the bowing curvature of the ends of the springs so as to vary the drawing tension of such ends of the spring upon the concave rubbing bed.

2. A washing machine including a base, uprights rising therefrom, a rotary rubbing drum supported by the uprights, a foraminous concave rubbing bed of resilient material embracing the lower portion of the drum, springs centrally supported upon the uprights and having downwardly curved or bowed ends connected with the side edges of the rubbing bed at opposite sides of the drum, brackets adjustably connected with the uprights, a pressure bar carried by said brackets and arranged to bear upon the springs on opposite sides of the uprights, and means for adjusting said bar for varying the bowing curvature of the springs and the drawing tension thereof on the concave rubbing bed.

3. A washing machine including a base, standards rising from the base, a shaft journaled on said standards, a foraminous drum carried by the shaft and provided with means for clamping an article thereto, a corrugated concave rubbing bed of resilient material embracing the lower portion of the drum, spring hangers having central portions resting on the uprights and curved or bowed end portions depending therefrom and attached to the upper edges of the bed, and means for exerting pressure upon the supported portions of the springs to regulate the resilient drawing pressure of the ends of the springs upon the edges of the bed.

4. A washing machine including a base, standards rising therefrom, a shaft journaled on said standards, a foraminous drum carried by the shaft and provided with article clamping means, a resilient corrugated concave rubbing bed embracing the lower portion of the drum, rods to which the edges of the bed are connected, bands extending around the bed and secured to the rods, suspension springs mounted on the uprights and permanently attached to the rods, and means for varying the tension of said springs.

5. A washing machine including a base, standards rising therefrom, a shaft journaled on the standards, a foraminous rubbing drum carried by the shaft, a resilient concave rubbing bed embracing the lower portion of the drum, hanger springs centrally supported upon the upper portions of the uprights and having curved or bowed end portions attached to the edges of the bed, a pressure bar extending between the uprights and bearing upon the springs for varying the degree of bowing curvature of the ends of the springs to regulate the drawing tension thereof, and means for adjusting said bar.

In testimony whereof I affix my signature.

JOHN W. SEIFERT.
